UNITED STATES PATENT OFFICE.

CLARENCE L. MATHEWS, OF COLTON, CALIFORNIA.

SETTING DEVICE.

1,064,354.

Specification of Letters Patent. Patented June 10, 1913.

Application filed June 19, 1911, Serial No. 634,136. Renewed October 23, 1912. Serial No. 727,453.

To all whom it may concern:

Be it known that I, CLARENCE L. MATHEWS, a citizen of the United States of America, residing at Colton, in the county 5 of San Bernardino, State of California, have invented a certain new and useful Setting Device; and I do hereby declare the following to be a full, clear, and exact description of the invention, such as will enable others skilled in the art to which it 10 pertains to make and use the same.

This invention relates to a setting device for watch mechanism; and it may be said to consist in the provision of the novel features and in the novel and improved construction, arrangement and combination of parts as will be apparent from the description and claim hereinafter.

An object of the invention is to provide a 20 novel and improved setting device which is positive in its operation and co-acts directly with the seconds hand and is adapted to be automatically operated by the yoke of either pendant setting or lever setting watch mechanism.

Further objects of the invention are to provide a novel and improved device of the nature specified which is practical and serviceable, simple in construction, economical 30 to manufacture, strong and durable in use, and effective in action.

Other objects and the advantages of the invention will be apparent to those skilled in the art, from a consideration of the following description, taken in connection with the accompanying drawing which is a partial view of watch mechanism with the invention applied thereto.

It will be evident that in setting the 40 hour and minute hands of watch mechanism to the correct time it is a desideratum that the seconds hand be set to begin movement in exact synchronism with the hour and minute hands at such correct time and therefore 45 by admit of the watch mechanism operating to indicate the time accurately to the second. To accomplish this end the novel and improved setting device now to be described may be used—it consisting broadly of a piv-

oted lever constructed and arranged to have 50 one end portion thereof in contact with the yoke of the watch mechanism and to have the other end portion thereof adapted to co-act directly with the seconds hand to stop the movement of the seconds hand in a pre- 55 determined position when said yoke is actuated.

In the construction of the device illustrated in the drawing the lever 36 is adapted to rock on pivot 37 suitably mounted on 60 stationary ears 38 and one end of the lever is pressed upwardly by a spring 38' and adapted to slidably engage with the beveled portion 39 on the underside of the yoke 3 and the other end of the lever is suitably 65 formed and provided with a pin 40 adapted to be moved through an opening 41 in the dial plate 42 to be interposed in the path of movement of the seconds hand when the end of the yoke adjacent to the setting wheel 70 is moved in the direction indicated by the arrow.

I claim:

The combination with time indicating mechanism including a dial plate, a seconds 75 hand, and a yoke, of stationary ears, a pivot bearing in said ears, a spring, a lever mounted on said pivot and arranged to be automatically operated by the yoke when the latter is actuated, said lever having one end 80 thereof pressed by said spring into engagement with a beveled portion on the underside of the yoke, and a pin at the other end of said lever, said pin adapted to move through an opening in the dial plate and be 85 disposed in the path of movement of the seconds hand when the lever is operated by the yoke, substantially as described.

In testimony whereof, I have signed my name to this specification in the presence of 90 two subscribing witnesses at Colton county of San Bernardino, State of California, this 12th day of June A. D. 1911.

CLARENCE L. MATHEWS.
